UNITED STATES PATENT OFFICE.

ROBERT A. PULFER, OF LOS ANGELES, CALIFORNIA.

SHOW-CASE.

No. 839,639.

Specification of Letters Patent.

Patented Dec. 25, 1906.

Application filed February 5, 1906. Serial No. 299,405.

To all whom it may concern:

Be it known that I, ROBERT A. PULFER, a citizen of the United States, residing at Los Angeles, in the county of Los Angeles and State of California, have invented a new and useful Improvement in Show-Cases, or which the following is a specification.

The main object of this invention is to provide a so-called "all-glass" show-case of improved construction wherein the glass plates will be securely held in their relative positions under normal conditions, but in such manner that when subjected to severe shock or strain said plates may move slightly relatively to one another without breakage.

Another object of the invention is to provide fastening means of this character which will be practically concealed or invisible, the said fastening extending between the glass plates at the joints thereof.

Another object is to provide cushions at the joints where glass meets glass and to make said joints dust-proof.

The invention comprises, in connection with the frame and glass plates of a case, binding devices attached to the frame and extending along and around the edges of said plates to hold the same firmly and yet not too rigidly to the frame.

The invention further comprises, in connection with such binding devices, fastening means for securing the plates to the binding devices at the corners or elsewhere.

The invention also comprises means for cushioning the glass plates from the binding devices.

The accompanying drawings illustrate the invention.

Figure 1 is a perspective of a square-corner show-case. Fig. 1^a is a detail plan of a corner-fitting thereof. Fig. 2 is a perspective of a round-corner show-case. Fig. 3 is a plan of a portion of a square-cornered case. Fig. 4 is an end elevation of a case, partly in section. Fig. 5 is a vertical sectional view on the line $x^5 x^5$ in Fig. 3. Fig. 6 is a detail sectional view on the line $x^6 x^6$ in Fig. 3. Fig. 7 is a vertical section on the line $x^7 x^7$ in Fig. 3. Fig. 8 is a perspective of a fastening plate or clip used for attachment of the binding devices to the frame of the show-case. Fig. 9 is a perspective of a tensioner for the binding devices. Fig. 10 is a perspective of one of the clamps, fittings, or fasteners for the plates at the junctions thereto. Fig. 11 is a

detail perspective of the binding-strip and cushioning device. Fig. 12 is a perspective of the binding means for a curved corner-plate. Fig. 13 is a perspective of a portion of a binding-strip used on top of a curved plate. Fig. 14 is a vertical sectional view showing a different form of tensioner for the binding devices. Fig. 15 is a vertical section on the line $x^{15} x^{15}$ in Fig. 14.

The frame of the show-case may be of any usual or suitable form, comprising, for example, a base 1 and a back member 2, said back member being formed as an open-work framing. In the form of show-case shown in Fig. 1 this back member is straight, and the glass plates of the show-case comprise end plates 3, front plates 4, and top plate 5. Fittings, clamps, or fasteners 6 are provided at the corners where the end, front, and top plates meet, said fittings engaging the respective glass plates, and binding devices are provided extending within the joints between the glass plates and attached to the frame or to other fittings so as to hold the plates in place on the frame. In case the show-case is sufficiently long to require it the front plate 4 may be made in a plurality of parts, and a fitting, clamp, or fastener 7 provided at the junction of said parts, said fitting engaging said parts and the top plate and being connected to the end fittings 6 by binding devices extending between the glass plates. These binding devices, which consist of ribbon or flat metal strips connecting the fittings to one another and to the frame, are not shown in Fig. 1, as they are concealed within the joints of the glass, but are shown in Figs. 3 to 7. In case of the end plate 3 the metallic strip 8 (see Fig. 4) is fastened by a plate 9 at its lower front end to the base 1 and extends up along the front edge of the plate 3 and back of the front plate 4 to the fitting 6 at the top of said plates. From said fitting the same strip or another strip leads over the top of the plate 3 to the rear member 2 of the case, where it is attached to a fastening-plate 9. Each fastening-plate 9 (shown in detail in Fig. 8) has two parallel slots 9^a to receive and engage the end portion of the binding strips or ribbon and has a hole 9^b to receive a screw 9^b for fastening the plate to the frame. The corner-fitting 6 is provided with means for clamping or gripping the three plates 3, 4, and 5 that meet at said corner, so that on suitably tensioning

the binding devices the said plates will be held toward and on the frame with a proper degree of firmness.

Each corner-fitting 6 is made in the form 5 of an angle-plate, having lugs 10 extending down at the outside of each arm for engagement with the outer faces of the glass plates and lugs 11 extending down at the inside of each arm for engaging the inside of said 10 plates, the outer flanges 10 having holes 10^a for the reception of a fastening bolt or screw 12 for a clamp arm or clip 13, adapted to engage over the top of the glass plate, this clip having a slot 12' to receive said screw, said 15 slot enabling adjustment of the clamp to tighten it on the top plate. The corner of fastening-plate 6 is rounded or bowed out to take the end of the front plate in Fig. 3. In the top of this fastening-plate 6 are slots 14 20 15, slot 14 being transverse to one or each arm of the said plate about in line with the inner edge of the other arm and slots 15 being near the outer end of said other arm and transverse thereto to receive and engage the 25 end portion of the metal ribbon or strip. The front lower end of the ribbon is secured to a plate 9 by threading through the slots 9' therein, first downwardly through the outer slot and then upwardly through the inner slot, and the other end of the strip is similarly secured to another plate 9, and the said 30 plates are then secured to the frame, as shown in Fig. 4, and also for the front part of the plate in Fig. 7, the glass end plate 3 being 35 placed on the frame and the said strip extending up in front of and over the same as described and through the slot 14 in the fitting 6, the length of the strip between these 40 points of fastening being such that when it is so fastened in place the plate will be firmly held, or, if desired, tensioning devices may be used to draw the strip tight after being put in place.

The glass wall-plates of the case are secured within or between shoulders or beads 45 16, where they contact with the frame. In order to facilitate the insertion of the front glass plate, it is desirable in some cases to provide for temporarily pushing back the 50 side or end plates. For this purpose the rear edge of said end plates has a certain amount of movement between its receiving-shoulders 16, and adjusting or tightening screws 17 are provided, working in the back member 2 of 55 the frame and bearing against a wooden strip 18, extending against the rear edge of said glass plate, so that on screwing in the screws the said strip will be pressed against the rear edge of said plate to shove the glass plate forwardly against the binding devices and the front plate. Cushioning means are provided 60 between the binding-strips and the several glass plates, said means consisting of any suitable yielding material, such as rubber or 65 felt, preferably in the form of a tube 19, sur-

rounding the ribbon or strips, except where it engages the fastenings, where the cushioning tube is stripped off, or, as shown in Fig. 14, strips 19' of felt may be placed on each side of the metal binding-strip between the vertical glass plates and said strip, a similar felt or other yielding strip being placed between the glass top plate and the metal strips and a yielding strip 19'', preferably of rubber, between the said metal strip and the top of the 70 glass wall-plates. This latter method of cushioning is particularly applicable to curved strips, such as shown in Figs. 12 and 13, and as therein shown the metal strip may have indentations 40 to engage the cushion-strips to prevent lateral displacement.

The corner-plates 6 are connected along the front of the case by a metallic binding-strip 8', connected at its ends to the respective corner-fasteners by engagement of the 85 slots 15 therein. In case the length of the case makes it desirable to build the front of more than one plate 4 the fitting or fastening plate 7 will be provided at the junction of the plates, said fitting having slots 15 at each end 90 thereof for engagement with and attachment to the metal strip leading to the two corner-fittings and also provided with slots 15' near the center thereof for engagement with and attachment of a strip 8^a, (see Fig. 6,) leading 95 downwardly between the two glass front plates 4 to the bottom of the case, the said vertical strip being in such case preferably provided with tensioning means, such as shown in Fig. 5, consisting of a plate 21, having slots 22 for engagement with the lower end portion of the ribbon and having a screw-threaded boss 23 for engagement with a screw 24, mounted in a plate 25, fastened by screws 25' on the base, so as to prevent endwise movement of the case and enabling the plate 21 to be moved up or down by rotation of the screw, the screw having a kerfed head 24' to enable its adjustment and a collar 26 engaging below said plate to hold the screw from endwise movement. The center fitting or fastener 7 is preferably provided with a reach bar or arm or brace-rod 29, extending 100 therefrom to the opposite side or back of the case, where it is fastened by screws 29', and has a clamp-plate 13', adjustably fastened thereto by screws 12, said plate 13' having a 105 flange 13^a to engage the top plate.

The fastener 7 is formed as a T-head on the reach-bar 29, said T-head having glass-engaging flanges at its front and rear edges, as shown in Fig. 10, and the clamp-plate 13' being fastened to the front flange. The arms of said T-head are formed with transverse slots 15 near their outer ends to receive and engage the binding-strip and with transverse slots 15' centrally thereof for the passage of the binding-strip from one or the other end 120 downwardly therethrough.

It will be noted that each of the binding- 125

strips extends between an edge of one glass plate and the face of an adjacent glass plate, the width of the strip being substantially equal to the width of the adjacent glass plate 5 edge, thereby securing an efficient support or connection between the plates and producing a substantially flush surface, so as to avoid any unsightly and dust-collecting crevices at the joint.

10 The show-case (shown in Fig. 2) has its end portions formed with square corners and formed similarly to construction above described in connection with Fig. 1. The front of the show-case is, however, round-cornered, 15 and at such round corners the construction is modified by making the binding-strip of curved shape to conform to the top edge of the corner-plate 39. This curved strip (shown at 30 in Figs. 12 and 13) has a flange 20 30' along its outer edge extending down to engage the outer face of the curved glass plate, and at each end this strip has an unflanged portion engaging in slots 15 in the fittings or fastening devices 7 37, fitting 7 being 25 of the form shown in Fig. 10 and having, preferably, a reach-bar 29, as above described, and the fitting 37 being similar to the fitting 7, but without the reach-bar, as the curved shape of the glass plate gives the 30 tensioning effect required. To each of these fittings a vertical binding-strip extending to the bottom of the frame or base is secured, as shown in Fig. 6, and tensioning devices are provided at the bottom thereof, as shown in 35 Fig. 5.

It will be noted that the tensioning devices above referred to are located on the inside of the case, so as to be accessible on opening the doors at the back of the case. In the form 40 of the tension device shown in Figs. 14 and 15 the said device is accessible from the outside of the bottom of the case and consists of a bolt 32, sliding vertically in a fixed sleeve 33 and having a flat extension 34, provided 45 with slots 35 to receive and engage the end portion of the binding-strip 8^a, said bolt having a nut 36 working thereon to draw it downwardly to tension the said strip.

By the constructions above set forth the 50 glass plates are bound or held firmly in the frame, and yet there is sufficient resiliency, due to the flexibility of the metallic binding devices, to enable the parts to yield slightly on occurrence of shock or jar, with the result 55 that the danger of breakage is reduced to a minimum. The construction is also dust-proof. The binding devices may be cemented to the strip and to the glass.

What I claim is—

60 1. In combination with a supporting-frame and a curved glass plate supported thereon, a curved strip extending over and conforming to the shape of said curved glass plate and having downwardly-extending

flange means engaging with the outer face of 65 said glass plate and means acting on the ends of said strip drawing the same tangentially and also downwardly.

2. The combination with a base, a curved glass plate supported thereon and glass plates 70 adjacent to said curved glass plate, with a curved binding-strip extending over and along the top of the curved glass plate, fittings at each end of the top of the curved glass plate and attached to the respective 75 ends of said curved strip, and binding devices attached at their lower ends to the base and binding devices at each end of the curved glass plate attached at its lower end to the base and extending up at the joint at that 80 end of said plate and through the fitting at the top of said joint and over the top of said joint and over the top of the adjacent plate, and means for putting the flexible binding devices under tension. 85

3. A binding device for glass plates comprising a metal fitting having two parallel slots extending transversely thereof near one end and provided near its other end with fastening means, and a flat metal binding- 90 strip threaded through said transverse slots from one side of the plate to the other and back again to engage the strip with the slots.

4. A binding device for glass plates comprising a fitting having glass-engaging flanges 95 and provided with two adjacent parallel slots extending transversely of the fitting, and a metallic strip threaded through said slots from one side of the plate to the other and back again to engage the strip with the slots. 100

5. A binding-fitting for glass plates having glass-engaging flanges, and provided near one end with two parallel slots extending transversely of the fitting and provided centrally of the fitting with another transverse 105 slot.

6. A binding-fitting for glass plates having two arms, each provided with glass-engaging flanges and each arm provided near its outer end with two parallel slots extending transversely of the fitting and each arm provided near its inner end with a slot extending transversely of the fitting. 110

7. A show-case comprising two adjacent glass wall-plates and a top plate and a binding device therefor, comprising a fitting having two arms, each arm provided with flanges for engaging the wall-plates and with means for engaging the top plate, one arm being provided near its outer end with two adjacent parallel slots extending transversely of the fitting and the other arm having a slot near its inner end extending transversely to said arm, a binding-strip extending between one of the wall-plates and the top plate and threaded through the said parallel slots from one side of the strip to the other and back again to engage the strip with the slots, and 120 125

another binding-strip extending between the other wall-plate and the top plate and longitudinally over the other arm and down through the transverse slot at the inner end 5 of said arm and between the two wall-plates.

8. A binding device for glass plates comprising a fitting having two arms, each arm having glass-engaging flanges, one arm being provided near its outer end with two adjacent parallel slots extending transversely of the fitting, and the other arm having a slot near its inner end extending transversely to the said arms, a binding-strip threaded through the said parallel slots from one side 15 of the strip to the other and back again to engage the strip with the slots, and a binding-strip extending longitudinally of the other arm and over the said arm and down through the transverse slot at the inner end of said 20 arm.

9. The combination with a supporting-frame comprising a case and a back member, a glass plate resting on said base and in contact with the back member, a strip connected 25 to the back member and extending forwardly over the top of the glass plate and down along the front edge of said plate, and means for attaching the lower end of said strip to the base and for adjusting the tension of said 30 strip, said means comprising a screw and a plate engaged by said screw, said plate having two parallel slots extending transversely thereof and the strip passing through said slots from one side of the plate to the other

and back again to engage the strip with the 35 plate.

10. In a glass show-case, the combination with a frame portion at one side of the case and a glass plate at the other side, of a reach-bar secured at one end of the frame and provided at its other end with a T-head having flanges to engage the glass plate, said T-head having at each end two parallel slots extending transversely to the head and having a transverse slot at its central portion, 40 and binding-strips engaging said parallel slots, one of said binding-strips passing through two of the slots from one side of the plate to the other and back again and extending longitudinally over the edge of the 45 glass plate.

11. A show-case comprising a frame at one side thereof and a plurality of glass plates at the other side, a reach-bar secured to the said frame and extending across the show-case and having at its end a T-head provided with flanges for engagement of the glass plate, and binding-strips extending over the edges of the said glass plates and engaging the T-head, one of said strips extending down between the glass plates.

In testimony whereof I have hereunto set my hand, at Los Angeles, California, this 26th day of January, 1906.

ROBERT A. PULFER.
